CARROLL STANSBURY, OF WAUWATOSA, AND GLENDON C. BROWN, OF MILWAUKEE, WISCONSIN, ASSIGNORS TO CUTLER-HAMMER, INC., OF MILWAUKEE, WISCONSIN, A CORPORATION OF DELAWARE

TIMING DEVICE

Application filed December 10, 1931. Serial No. 560,092.

This invention relates to electric timing devices and is especially applicable to timers for electric welders, though not limited thereto.

In the co-pending application of LeVan and Stansbury, Serial No. 417,969, filed January 2, 1930, a system is described in which current is supplied to a translating device for an adjustable time, the time being controlled through an electron tube, the discharge of which is affected by the energy stored in an energy storage circuit connected to the control grid of said tube. While the system illustrated therein is applicable to various uses it has, under certain operating conditions, the disadvantage that it permits the operator to interfere with the normal timing of the apparatus. The system referred to also requires a relatively large energy storage capacity which is greatly reduced by the present invention.

In the system of Fig. 2 of the aforementioned application, it will be noted that a controlling tube is conducting at all times except during a definite period after the opening of a pilot switch until the time when the potentials of the control grid has reached a sufficiently low value to again permit passage of current through said tube. If, therefore, the pilot switch is again closed before the tube has become conducting through the action of the grid, the closure of the pilot switch immediately changes the grid potential, to a value which thereby shortens the time during which the tube is non-conducting. Such action is especially disturbing if the pilot switch is used to control the current to a welder, as the weld may then receive an insufficient amount of energy to produce a sound joint.

It has also been found that during the negative half cycle of the charging period of the energy storage circuit the latter partially discharges thus requiring a relatively large capacity of the storage circuit to accomplish the desired results.

The improved system which is illustrated in the accompanying drawing in connection with a welding machine is a modification of that illustrated in Fig. 2 of the aforementioned application.

The present invention has for its object to increase the accuracy with which the grid controls the starting of passage of current through the electron tube.

Another object is to provide improved apparatus for controlling the timing function.

Another object is to provide apparatus which will make it impossible for the operator to interfere with the normal functioning and to insure correct timing irrespective of the actuation of the pilot switch which is under his control.

Another object is to provide apparatus which requires a minimum capacity for the energy storage circuit.

Another object is to provide a system which very sharply responds to the change of conditions in the energy storage circuit thereby insuring very accurate timing.

In the drawing, Figure 1 is a diagrammatic view of the system embodying my invention, while

Fig. 2 shows the voltage relations of the system.

Referring to Figure 1, 1 is a welding transformer having a primary winding 2 and a secondary winding 3. The secondary winding 3 is connected to the jaws 4 of the welding machine. Preferably adjacent to the welder is provided a normally closed push button switch 5. Lines L¹ and L² are the terminals of an alternating current supply. A magnet switch 6 has a winding 7 and normally open cooperating contacts 8 and 9 which are connected in series with the winding 2 across the supply lines L¹ and L². A relay 10 has a magnet winding 11, normally closed main contacts 12, normally open auxiliary contacts 13 and normally closed auxiliary contacts 14. The system further includes an electron tube 15 preferably of the gaseous type having a cathode 16, which may be heated in any well known manner, an anode 17 and a control grid 18. The winding 7 of switch 6 has one terminal connected to the line L¹ while its other terminal is connected through the contacts 12 to the line L². The winding 11 of relay 10 has one terminal connected to line L¹ while the other terminal is connected to the anode 17, the cathode 16 being connected to

to line L^2 . A condenser 19 has its one terminal 19^a connected to the grid 18 while the other terminal 19^b is connected through the resistance 20 to line L^2 , and through the resistances 21 and 22 to line L^1 . An adjustable resistance 23 is connected between the grid 16 and the normally closed contacts 14, which in turn are connected to terminal 19^b of the condenser. One contact of push button switch 5 is connected to the common terminal of resistances 21 and 22, while the other contact of said push button switch is connected through the normally open contacts 13 to the condenser terminal 19^b.

15 The system operates in the following manner:

When it is desired to make a weld, the material to be welded is introduced between the jaws 4 and the latter are pressed together.

20 A current normally flows from line L^1 through winding 11 of switch 10 through the tube 15 to line L^2 during positive half cycles of the alternating current.

Prior to the welding operation, the grid 25 18 of tube 15 is of such potential as not to impede current flow during the positive half cycle of the alternating current for the following reasons: Due to the drop of voltage through the resistance 20 a positive potential!

30 with respect to the cathode 16 is impressed upon a condenser plate 19^b whose instantaneous value is equal to the instantaneous drop through said resistance. This results in a negative charge of the condenser plate 19^a of 35 a corresponding value. Superposed upon this negative potential, due to the charge on the condenser is, however, the alternating positive potential aforementioned due to the voltage drop through the resistance 20 so that

40 the resulting potential of the grid 18 is not sufficiently negative to prevent discharge of the tube at the same moment of the positive half cycle. As a result, the contacts 12 are open and no current can flow through coil 7

45 of relay 6 so that the primary winding 2 of the welding transformer does not receive any current from the line. If the operator then wishes to apply current to the weld he pushes push button switch 5 thereby opening a circuit from the junction point of resistances 21

50 and 22 through push button switch 5, contacts 13 to condenser terminal 19^b thus inserting resistance 21 in series with resistances 22 and 20. The potential of the condenser terminal 55 19^b is thus suddenly reduced, due to the change in voltage drop through the resistance 20, causing a corresponding drop of the potential of condenser terminal 19^a to a negative value which is sufficient to prevent re-

60 starting of discharge through the tube on the succeeding positive half cycles. The coil 11 thereby becoming de-energized causes closure of normally closed contacts 12 thereby energizing switch 6 and completing the current supply to the welding transformer 1 so that

now the welding jaws receive current. De-energization of switch 10 also opens contact 13 so that the aforedescribed circuit around resistance 21 remains open even though the operator releases the button 5. The condenser 19 gradually discharges over a circuit from plate 19^b through contacts 14, which are now closed due to the de-energization of switch 10, resistance 23 to condenser plate 19^a. After a certain lapse of time, the potential of condenser plate 19^a and grid 18 connected therewith has again been reduced to a value which permits the tube 15 to conduct current during the positive half cycle, whereupon the switch 10 is energized thereby interrupting the current through contacts 12 and this in turn interrupts the current supply to switch 6 which interrupts the current of the welding transformer. It will be apparent that irrespective of the operation of the push button switch 5 the time during which the tube 15 remains non-conducting after initial operation of said push button switch remains constant and therefore a constant amount of energy is supplied to the welder.

It has been found that by providing for opening of the condenser discharge circuit at the switch 14, the condenser plate 19^b can be charged to the full potential of line L^1 less the drop in resistance 22 and thus the maximum possible negative potential is attained by the plate 19^a and the grid 18. If this discharge circuit were closed at all times the current flowing in resistance 23 would produce an additional drop in resistance 22 thereby reducing the potential available to charge the condenser. Furthermore, the partial discharge of the condenser through resistance 23 during the intermediate periods is obviated. By opening this discharge circuit the condenser plate 19^b is thus charged to the highest potential available. This permits a reduction of the size of the condenser which is necessary to obtain a given timing period. The assurance of raising the charge on the condenser always to the maximum value reduces the variation in timing due to imperfect rectification of the cathode-grid path, and this is of special importance for short period timing adjustment.

Referring now to Fig. 2, E_p is the voltage impressed upon the main electrode of the tube during the positive half cycle, E_1 is the grid voltage necessary to prevent the tube from conducting, E_c is the voltage of the condenser after it has been charged to its maximum negative value by the depression of the push button 5, while E_g is the grid voltage which is equal to the condenser voltage plus the alternating component of the voltage drop through the resistance 20 due to the current passing through the resistances 20, 21 and 22. It will be noted that this superposed alternating voltage is in phase with the plate voltage E_p and produces at the beginning of the

positive half cycle a greater rate of change than the rate of change of the condenser voltage alone. This causes a relatively rapid change of the grid voltage at the beginning 5 of that half cycle when the latter becomes more positive than the voltage E_1 , thereby producing a very positive controlling effect on the tube. Furthermore, the grid voltage during each positive cycle reaches a value, 10 which approaches the critical voltage more closely than the condenser discharge voltage, so that the former is reached and the tube is rendered conductive when the rate of change of the condenser voltage is still relatively 15 high. This results in a more accurate timing than would be possible without the biasing voltage.

The time during which the welder is supplied with current may be adjusted by adjusting the discharge resistance 23 or the condenser 19.

What we claim as new and desire to secure by Letters Patent is:

1. In combination, a power supply, a translating device supplied thereby, an electron tube controlling the continuity of circuit thereof and having a control electrode, means to impress upon said electrode a potential rendering said tube conductive to effect completion of the circuit of said translating device, energy storing and discharging means associated with said electrode and having a transient effect thereon to cause said tube to interrupt said circuit of said translating device and means associated with said translating device to complete a circuit to effect discharge of said storing means upon interruption of said last mentioned circuit.

2. In combination, a power supply, a translating device supplied thereby, an electron tube controlling the continuity of circuit thereof and having a control electrode, means to impress upon said electrode a potential rendering said tube conductive to effect completion of the circuit of said translating device, energy storing and discharging means associated with said electrode and having a transient effect thereon to cause said tube to interrupt said circuit of said translating device, means to commutate the connection of said energy storing means and means associated with said translating device to complete a circuit to effect discharge of said storing means upon interruption of said last mentioned circuit.

3. In combination, a power supply, a translating device supplied thereby, an electron tube controlling the continuity of said circuit thereof and having a control electrode, means to impress upon said electrode a potential rendering said tube conductive to effect completion of the circuit of said translating device, energy storing and discharging means associated with said electrode and having a transient effect thereon to cause said tube to

interrupt said circuit of said translating device, manual means to commutate the connection of said energy storing means and means associated with said translating device to complete a circuit to effect discharge of said storing means upon interruption of said last mentioned circuit. 70

4. In combination, a power supply, a translating device supplied thereby, an electron tube controlling the continuity of circuit thereof and having a control electrode, means to impress upon said electrode a potential rendering said tube conductive to effect completion of the circuit of said translating device, energy storing and discharging means 80 associated with said electrode and having a transient effect thereon to cause said tube to interrupt said circuit of said translating device, manual means and additional means associated with said translating device and in 85 series with said manual means to commutate the connection of said energy storing means and means associated with said translating device to complete a circuit to effect discharge of said storing means upon interruption of 90 said last mentioned circuit.

5. In combination, a power supply, a translating device supplied thereby, an electron tube controlling the continuity circuit thereof and having a control electrode, means to impress upon said electrode a potential derived from said supply for rendering said tube conductive to effect completion of the circuit of said translating device, and energy storing and discharging means associated with said electrode and having a transient effect thereon to cause said tube to interrupt the circuit of said translating device for a given period, said first mentioned means including means to superpose a potential varying with the potential of said supply upon the control electrode during said given period. 100 105

6. In combination, an alternating current supply, a translating device supplied thereby, an electron tube controlling the continuity of circuit thereof and having a control electrode, means to impress upon said electrode a potential derived from said supply for rendering said tube conductive to effect completion of the circuit of said translating device, and energy storing and discharging means associated with said electrode and having a transient effect thereon to cause said tube to interrupt the circuit of said translating device for a given period of time, said first mentioned 110 115 means including means to superpose an alternating potential which is in phase with the potential of said alternating circuit upon the control electrode during said given period. 120

7. In combination, a power supply, a translating device supplied thereby, an electron tube controlling the continuity of circuit thereof and having a control electrode, means to impress upon said electrode a potential rendering said tube conductive to effect comple- 125 130

- tion of the circuit of said translating device, energy storing and discharging means associated with said electrode and having a transient effect thereon to cause said tube to interrupt said circuit of said translating device for a given period and means associated with said translating device to complete a circuit to effect discharge of said storing means upon interruption of said last mentioned circuit, 5
 10 said first mentioned means including means to superpose a potential varying with the potential of said supply upon the control electrode during said given period.
8. In combination, a power supply, a translating device supplied thereby, an electron tube controlling the continuity of circuit thereof and having a control electrode, means to impress upon said electrode a potential rendering said tube conductive to effect completion of the circuit of said translating device, energy storing and discharging means associated with said electrode and having a transient effect thereon to cause said tube to interrupt circuit of said translating device 15
 20 for a given period, means to commutate the connection of said energy storing means, means associated with said translating device to complete a circuit to effect discharge of said storing means upon interruption of the
 25 last mentioned circuit, said first mentioned means including means to superpose a potential varying with the potential of said supply upon the control electrode during said given period.
- 30 9. In combination, an alternating current supply, a translating device supplied thereby, an electron tube controlling the continuity of circuit thereof and having a control electrode, means to impress upon said electrode a potential rendering said tube conductive to effect completion of the circuit of said translating device, energy storing and discharging means associated with said electrode and having a transient effect thereon to cause said tube to interrupt circuit of said translating device for a given period, means to commutate the connection of said energy storing means, means associated with said translating device to complete a circuit to effect discharge of said storing means upon interruption of the last mentioned circuit, said first mentioned means including means to superpose an alternating potential which is in phase with the potential of said alternating supply upon the control electrode during said given period.
- 35 10. In an electric welding system adapted to supply current to the material to be welded for an adjustable time, in combination, a power supply, a pair of welding jaws receiving energy from said supply, an electron tube controlling the continuity of circuit thereof and having a control electrode, means to impress upon said electrode a potential for varying the conductivity of said tube to effect

11. In an electric welding system adapted to supply current to the material to be welded for an adjustable time, in combination, a power supply, a pair of welding jaws receiving energy from said supply, an electron tube controlling the continuity of circuit thereof and having a control electrode, means to impress upon said electrode a potential rendering said tube conductive to effect interruption of circuit to said jaws, energy storing and discharging means associated with said electrode and having a transient effect thereon to cause said tube to effect completion of circuit to said jaws for a given period of time and means associated with said first mentioned means to complete a circuit to effect discharge of said storing means upon completion of the circuit to said jaws.
12. In an electric welding system adapted to supply current to the material to be welded for an adjustable time, in combination, an alternating current supply, a pair of welding jaws receiving energy therefrom, an electron tube controlling the continuity of circuit thereof and having a control electrode, means to impress upon said electrode a potential derived from said supply for rendering said tube conductive to effect interruption of the circuit to said jaws, energy storing and discharging means associated with said electrode and having a transient effect thereon to cause said tube to effect completion of the circuit to said jaws for a given time, said first mentioned means including means to superpose an alternating potential which is in phase with the potential of said alternating circuit upon the control electrode during said given period.
13. In an electric welding system adapted to supply current to the material to be welded for an adjustable time, in combination, an alternating current supply, a pair of welding jaws receiving energy from said supply, an electron tube controlling the continuity of circuit thereof and having a control electrode, means to impress upon said electrode a potential rendering said tube conductive to effect interruption of circuit to said jaws, energy storing and discharging means associated with said electrode and having a transient effect thereon to cause said tube to effect completion of the circuit to said jaws for a given period of time, means to commutate the connection of said energy storing means, means associated with said energy storing

and discharging means to complete a circuit to effect discharge of said storing means upon an initiation of current supply to said jaws, said first mentioned means including means 5 to superpose an alternating potential which is in phase with the potential of said alternating supply upon the control electrode during said given period.

In witness whereof, we have hereunto sub-
10 scribed our names.
